HIS ATTORNEY

UNITED STATES PATENT OFFICE

SAMUEL ROTBERG, OF CHICAGO, ILLINOIS

DRINKING CUP FOR BIRDS

Application filed January 12, 1931. Serial No. 508,203.

This invention relates to certain novel improvements in drinking cups for birds, and has for its principal object the provision of an improved construction of this character which will be highly efficient in use and economical in manufacture.

Among the several objects of this invention is the provision of an improved drinking cup for birds which is highly sanitary in use. 10 Another object of the invention is the provision of an improved construction which permits a bird to drink therefrom without polluting the water in the cup, thereby preventing the spread of numerous infectious and contagious diseases which has been a common and serious defect in the drinking appliances for birds known and used heretofore in the art. 15

A further object of the invention is the provision of an improved drinking cup for birds which is so arranged that it is impossible for the bird to splash his feathers or feet in the cup while drinking from the same. 20

An additional object of the invention is the provision of an improved construction of the character described herein which is so arranged that the interior of the cup and the level or height of the water therein may be seen from the exterior. 25

30 Other objects will appear hereinafter.

The invention consists in the novel combination and arrangement of parts to be hereinafter described and claimed.

The invention will be best understood by 35 reference to the accompanying drawing showing the preferred form of construction, and in which:

Fig. 1 is a perspective view depicting a preferred form of construction of the invention; 40

Fig. 2 is a sectional view substantially on the line 2-2 in Fig. 1; and

Fig. 3 is a sectional view substantially on the line 3-3 in Fig. 2.

45 Referring to the drawing wherein a preferred embodiment of the invention is depicted, indicated at 10 is a housing which may be of any suitable material and of any suitable shape so as to define a front wall 11. An opening 12 is provided in the front wall 11,

and disposed over the opening 12 is a transparent plate 13 which may be of any desired shape so as to be secured to the front wall 11 by suitable means, such, for example, as an adhesive. 55

There is provided on the front wall 11, and unitary therewith, a frame generically indicated at 28. The frame 28 includes an upper wall 14 which depends angularly from the wall 11 and the side walls of the frame 28 are provided by diverging flanges 15 and 16 which project outwardly from and are integral with the front wall 11, while these walls 15 and 16 are likewise integral with the top wall 14 of the frame 28. 60

65 Projecting angularly outward and upward from the front wall 11 is a lip 17 at the outer end of which is an upstanding portion 18. It is manifest, therefore, that the walls 14, 15, 16, and 18 define an opening 19 in the front wall of the housing 10. 70

The present invention includes a cup, generically indicated at 20. The cup 20 includes a lower wall 21 which is mounted on and supported by the wall 18, this bottom wall 21 being secured in position by means of suitable adhesive as indicated at 22. The cup 21, in the present instance, is arcuate in cross section so as to define a vertical wall 23 which includes a portion 24 that is adhesively secured to the side wall 15. The vertical wall 23 of the cup includes a portion 25, similar to the portion 24, and this portion 25 is adhesively secured to the side wall 16. 75

No vent opening is provided in the housing 10 and obviously, therefore, when the housing 10 is inverted and filled with water, which is inserted through the open upper side 26 of the cup 21, the water will remain therein since the air pressure on the open upper side 26 of the cup will support the water in the housing 10 while allowing the water to feed down into the cup 21 through the open rear side 27 of the cup. Manifestly, therefore, a bird may drink from the cup 21 since the upper side 26 thereof is open while it is impossible for the bird to stand in the cup or to shake its feathers therein. 95

It will be seen, therefore, from the foregoing description of my invention that I have 100

provided an improved drinking cup for birds which, while being economical in construction is highly sanitary in use and therefore a decided improvement over the heretofore existing art.

5 While I have illustrated and described the preferred form of construction for carrying my invention into effect, this is capable of variation and modification without departing 10 from the spirit of the invention. I, therefore, do not wish to be limited to the precise details of construction set forth, but desire to avail myself of such variations and modifications as come within the scope of the appended claim.

15 Having thus described my invention, what I claim as new and desire to protect by Letter Patent is:

20 A drinking appliance for birds comprising a liquid containing housing including a front wall having an opening therein, and said wall being provided with another opening above the first named opening, diverging flanges integral with said front wall and projecting outwardly therefrom to define side walls about said first named opening, a depending flange integral with said front wall and defining a top wall over said opening, an 25 outstanding flange integral with said front wall and including an upstanding portion providing a supporting base, a cup mounted on said base, having an open upper side and including a vertical wall, said vertical wall including ear portions adapted to be secured to said side walls, said cup having an open inner side communicating with said housing, and a transparent plate over the second-named opening whereby the level of the liquid in the housing may be seen.

30 In testimony whereof I affix my signature.
SAMUEL ROTBERG.
